UNITED STATES PATENT OFFICE.

GEORGE A. DEAN, OF DORCHESTER, MASSACHUSETTS.

HORSESHOE.

SPECIFICATION forming part of Letters Patent No. 295,620, dated March 25, 1884.

Application filed August 9, 1883. (No model.)

To all whom it may concern:

Be it known that I, GEORGE A. DEAN, a citizen of the United States of America, residing at Dorchester, in the county of Suffolk and State of Massachusetts, have invented certain new and useful Improvements in Horseshoes; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 This invention relates to certain new and useful improvements in horseshoes, its object being to provide a shoe which can be readily attached to a horse's hoof, which shoe is provided at its toe with a dovetailed recess, and 20 near the heel with slots which are provided with transverse perforations, to which shoe may be attached a supplemental shoe which is provided with an upwardly-projecting toe-piece with beveled edges, and at the heel with 25 upwardly-projecting portions which are rigidly attached to the lower shoe, so that a pad may be secured between the parts, so as to protect the lower portion of the horse's hoof, as will be hereinafter more fully set forth, and 30 pointed out in the claim.

In the accompanying drawings, which illustrate my invention, Figure 1 is a perspective view, showing my improved horseshoe attached to a horse's hoof. Figs. 2, 3, and 4 35 are detailed views of the parts detached.

A represents the portion of the horseshoe which is attached to the horse's hoof in the usual manner, said shoe being provided at its front portion or the toe with a cut-away portion, *a*, having beveled sides, as shown. Near 40 the heel of this shoe I provide slots *b*, which may extend through the shoe, and are provided with transverse perforations *b'*. The lower shoe is provided on its under side, when 45 desirable, with the usual calks. On its upper side this shoe *B* is provided at the toe portion with an upwardly-projecting portion, *c*, having beveled sides, as shown, so as to correspond with the recess *a* in the portion of the

shoe *A*. This shoe *B* is also provided with 50 upwardly-projecting blocks *d*, which correspond in shape with the slots *b* in the shoe *A*. These blocks are provided with transverse perforations, as shown.

C represents the pad, which may be made 55 of leather, rubber, or other suitable material, and the same is provided with openings *e e*, through which pass the blocks *d*, and the same is cut away at its front portion, as shown at *f*. This pad is for the purpose of protecting the 60 frog of the hoof, and when applied to the shoe forms a pocket, in which may be placed materials saturated with medicaments for the cure of diseases of the hoof. This pad will also prevent dirt from coming in contact with the 65 under portion of the hoof, and will prevent snow from balling upon the exterior portion.

The shoe *A*, as hereinbefore referred to, is first attached to the hoof by nails in the usual manner. The leather *C* is then placed upon 70 the shoe *B*, after which the parts are united to each other, which may be done in the following manner: The shoe *B*, which carries with it the portion *c*, is placed at an angle, so that the portion *c* will enter the recess *a*. It is then brought flat against the shoe *A*, the blocks *d* entering the slots *b*. A pin, which may be screw-threaded at its end, is then passed through each perforation *b'*, thus securing the 75 parts firmly to each other.

Having thus described my invention, what I claim as new, and desire to secure by Letters Patent, is—

The improved horseshoe and pad herein described, consisting of the shoe *A*, having a recessed front portion, and slots located near the heel of the shoe, in combination with the shoe *B*, having upwardly-projecting toe-piece *c* and perforated blocks *b*, and pad *C*, with recess *f* at the toe, and slots *e e*, the parts being adapted to be united to each other, substantially as shown, and for the purpose set forth.

In testimony whereof I affix my signature in presence of two witnesses.

GEORGE A. DEAN.

Witnesses:

WILLIAM F. ANNABLE,
CHAS. HOYT.
